CARBURETOR

Original Filed April 24, 1922

UNITED STATES PATENT OFFICE

FRANK C. MOCK, CHARLES J. GUSTAFSON, AND MILTON E. CHANDLER, OF CHICAGO,
ILLINOIS, ASSIGNORS TO BENDIX STROMBERG CARBURETOR COMPANY, OF CHICAGO,
ILLINOIS, A CORPORATION OF ILLINOIS

CARBURETOR

Application filed April 24, 1922, Serial No. 556,160, and in Great Britain September 6, 1919. Renewed
April 2, 1930.

The present invention relates to improvements in carburetors, and is a continuation in part of our co-pending Patent No. 1,620,827, for which the application was filed July 10, 1918.

One of the particular objects of the invention is to provide a fuel nozzle so related to the carburetor structure that the port opening thereof can be moved or shifted, as for 10 the purpose of bringing the port under a greater or lesser degree of suction influence.

A further object is to provide a particular arrangement of nozzle for carrying the above object into effect, this nozzle being preferably in the form of an adjustable plug or the like separate from the body of the carburetor.

In the present form, which is merely illustrative, the invention is embodied in the conventional type of idling device which is generally employed in plain tube carburetors and which is usually arranged to discharge in the immediate vicinity of the throttle. It is well known that in such carburetors there 20 is an extremely wide variation of suction on the main nozzle. The performance of an airplane carburetor is typical, the suction on the main nozzle varying approximately as the 25 6th power of the engine speed under the propeller load. From approximately one-half speed down there is generally not enough suction on the main nozzle to accurately meter the mixture. Consequently, during this range 30 the point of feed must be from the idling 35 nozzle above or at the upper edge of the throttle. From this it will be noted that during a considerable part of the running period, and over a considerable portion of the range 40 of speeds, the idling nozzle is the primary 45 source of fuel supply and should, therefore, meter the proportions with substantially the 50 same degree of accuracy required of the customary main nozzle. The control of speed during this portion of the range is obtained 55 by a comparatively small movement of the 60 throttle, which requires that the idling nozzle be located with certain exactness relative 65 to the throttle to accurately control the range 70 of suction at this nozzle during this 75 comparatively small movement. Added to this

is the further difficulty that the suction above the throttle diminishes with the movement of opening the throttle owing to the greater volume of air admitted. This is the direct converse of what is desired at the idling nozzle, 55 because during this time a higher suction is desirable at the nozzle for drawing the increased amount of fuel required for the greater volume of air. During the operation of the throttle, there should be a gradual transition or blending from the operation of one nozzle to the operation of the other, otherwise lean charges or charges of pure air may be admitted owing to the idling nozzle diminishing or discontinuing its feed before the 60 main nozzle takes up operation. Hence, the idling nozzle should be capable of feeding an increased volume of fuel during a certain range of the throttle movement, despite the 65 lowering of the suction above the throttle. 70

This, or practically any other variation of idling nozzle feed can be secured by utilizing differentially the relatively high suction existing above the throttle and the relatively low suction existing below it. For example, only a small portion of the nozzle opening may be subjected to the suction above the throttle during very slow running, and with the opening movement of the throttle a greater portion of the nozzle opening 75 may be subjected to the higher suction above the throttle. The configuration of the nozzle opening may be such that for a given engine speed a certain proportion of the nozzle opening 80 will be subjected to suction above the throttle and a certain proportion to the suction below the throttle. Shifting of the 85 throttle towards an open position increases the proportion of nozzle opening subjected to suction above the throttle and decreases the proportion of nozzle opening exposed to suction below the throttle. 90

It will be apparent that to obtain this accurate control of the idling nozzle feed a very accurate location of the nozzle relative to the throttle is essential. In the case of the ordinary butterfly throttle, when the 95 throttle is in a closed or restricted position its edge contacts or moves toward the wall of the carburetor barrel on an angle closely

approaching a tangent. Consequently, any variation of even minute degree in the bore of the carburetor will result in the throttle edge contacting with the carburetor wall at a higher or lower point along the length of the wall. To take care of this condition it is necessary that relative adjustment be afforded between the throttle and idling nozzle, if accuracy of mixture proportion is to be obtained.

In the present construction, and as broadly disclosed in our above mentioned patent, we have provided an arrangement of idling nozzle which can be moved relative to the carburetor casting, preferably by rotation of the nozzle, so as to selectively dispose the nozzle openings in different positions relative to the edge of the throttle. Thus, the nozzle opening can be moved to withdraw it or a portion thereof from the influence of the suction above the throttle, or to increase the area of nozzle opening subjected to this higher suction, or to confine a greater or less extent of the nozzle opening to the differential suction existing at the lip of the throttle. This conception of an idling nozzle adjustable with respect to the influence of suction thereon, has the further possibility of permitting the nozzle opening to be shifted longitudinally of the valve, as we have above stated, for the purpose of increasing the area of nozzle opening subjected to the suction of one side of the throttle and decreasing the area of nozzle opening subjected to the suction of the other side of the throttle.

This conception of an adjustable idling nozzle has convenient and simple adaptation in the form of a plug which seats in an opening in the carburetor body and is removable for convenient substitution and adjustment. By inserting the plug at different angles or rotating it to these angles, the port opening can be disposed in any desired position relative to the edge of the throttle. This port opening may be of such configuration and so located in the plug that the angular adjustment of the plug will raise or lower the opening relative to the throttle or dispose different areas of port opening above or below the throttle. A closure plug is preferably employed to close the outer end of the opening in which the idling plug is seated, this closure plug holding the idling plug in any of its various positions of adjustment and closing the outer end of the aforesaid opening in which the nozzle plug is disposed. While this is the preferred manner of accomplishing the objects set out above, it will be obvious that the same can be accomplished by other arrangements of the jet. In the drawing illustrating the present embodiment:

Figure 1 is a fragmentary sectional view of a carburetor embodying our invention, illustrating the relation of nozzle plug and

closure plug disclosed in our Patent 1,620,827.

Fig. 2 is a fragmentary sectional view on an enlarged scale of a modified construction, and Fig. 3 is an elevational view of the face of the nozzle plug as viewed from the interior of the carburetor barrel, the position of the throttle across the plug being shown to illustrate the manner of adjustment of the plug.

Figs. 4 and 5 are views similar to Figs. 2 and 3, but showing a modified construction of plug.

Figs. 6 and 7 are views similar to Figs. 2 and 3 showing a modified construction of plug wherein the nozzle opening is formed by milling one side of the plug away; and

Figs. 8 and 9 are views similar to Figs. 2 and 3 of still another modified construction of plug.

The particular form of carburetor illustrated in Figure 1 is selected for illustrating a typical embodiment simply because it forms the subject-matter of our above mentioned patent; it being obvious that the present invention is capable of embodiment in practically any type of carburetor. A specific description of this carburetor being available in said patent, suffice it to say here that it comprises a body portion or casting 15, having an air intake 16 and a mixture outlet 17. A throttle 18 controls the mixture outlet 17, and a main nozzle 19 discharges into the innermost of two concentric venturis 21 and 22. The idling nozzle, which is designated 23 in its entirety, discharges into the mixture passageway 20 in close proximity to the edge of the throttle 18. This idling jet draws fuel thru a tube 24, which is secured at its lower end in a plug 25, the tube having a lateral hole 26 which also extends thru the plug for admitting fuel to the tube. Fuel is supplied to both the main jet and idling jet from a float chamber 27 which discharges thru a passageway 28 into the center of the main nozzle 19 and into an accelerating well 29 surrounding said nozzle. The idling nozzle 23 draws from this accelerating well thru a passage 31.

Referring to the particular construction of the idling nozzle, it will be noted that the nozzle is arranged in a relatively large hole which is formed to extend thru the side wall of the casing 15 adjacent the point where the lower lip of the throttle 18 comes into approximate contact with the side wall of the passageway 20 when the throttle is in its restricted position. This bore 32 has an enlarged counterbore 32' which is threaded at its outer end. Fitting in this bore is a nozzle plug 33 having reduced portions extending into the bore 32 and counterbore 32' and an enlarged flanged portion seating against the inner end of the counterbore 32'. This plug is backed up and held in any position in which it may be adjusted by a threaded closure plug 34 which screws into the threads

- in the end of the counterbore 32' and abuts the rear end of the nozzle plug 33. The nozzle plug 33 has a transverse hole 35 which communicates by way of the slot 36 with the mixture passageway 20, this slot 36 lying in proximity to the lip of the throttle valve 18 when the same is in closed or restricted position. The plug 33 has a bore 37 thru which the fuel mixture for idling passes on its way 5 into the engine manifold. The plug has a lateral recess 38 lying immediately above the tube 24, which tube may have a plug restriction 39 in its upper end if desired. A channel or annular space 41 is formed about 10 the outer end of the plug 33, this channel or annular space forming an air space for air which is admitted by way of the port 42, valve port 43, and radial port 44 in the plug 34. 15
- 20 A needle valve 45 is threaded into the hub of the plug 34 for controlling the amount of air which enters by way of the port 42, which air in connection with that passing through slot 36 and the liquid fuel entering from the tube 24 forms a mixture for supplying the engine during idling. This needle valve comprises a suitable cylindrical stem which is threaded to fit within the boss extension on 25 the end of the plug 34, and has a slot or other suitable means for applying an adjusting tool, such as a screw driver. This valve member has a diametrical hole near the end of the same, a spring 46 and a pair of spherical rollers 47 lying in said bore. The interior 30 of the hub extension on the end of the plug 34 is provided with a series of longitudinal grooves into which the rollers 47 tend to seat under the influence of spring 46. This construction is formed by first drilling a series of holes—for instance, six in number—with centers lying on a circle which is substantially equal to the diameter of the valve. A large hole is then drilled with its bore substantially equal to the diameter of the valve, 35 said hole cutting across the series of smaller holes, thereby forming a plurality of longitudinal seats or grooves, which are adapted to hold the rollers 47 and thus the valve 45 against movement. The plug 34 has an extending flange 49 having aperture 51 thru which a releasable wire clip 52 may be extended for preventing rotation of the plug 34 after the same has been screwed into position. 40
- 50 When the throttle 18 is in its restricted position with the lower lip thereof substantially intersecting the slot 36, as shown, it will be apparent that a certain rate of fuel feed will occur thru the slot 36 depending upon the suction above the throttle, the suction below the throttle and the velocity of air around the throttle lip thru the slot 36. It will be observed that by turning the plug 33, a greater or less area of the slot 36 is brought into 45 alignment with the lower lip of the throttle. 55
- This brings a greater or lesser proportion of the slot area under the influence of the suction existing around the edge of the throttle. Thus, by changing the angle of the plug 33 and its slot 36, different rates of fuel feed can be obtained. The channel or annular space 41 maintains communication with the upper end of the tube 24, or rather the restricted plug 39, so that fuel flow will be maintained even though the plug 33 is adjusted thru a wide angle. The separate mounting of the plug 33 in the casting obviously permits of this adjustment with little difficulty, and after the plug has been properly adjusted it is secured firmly in position by 60 screwing the closure plug 34 hard against it. 70
- 75 This practice of making the idling nozzle in a separate plug also possesses the advantage that the plugs may be easily substituted for plugs having larger or smaller or differently shaped orifices. Thus, by a simple removal of the outer plug 34, the nozzle plug 33 may be removed and a plug having a larger or smaller or differently formed fuel opening may be quickly substituted. 80
- 85 In Figures 2 and 3 we have illustrated a modified construction. Here the adjustable and removable nozzle plug 72 is of relatively shallow depth and the fuel passageway 24' enters the plug bore behind the plug 72. The fuel passes thru a number of holes 55' into the interior of the outer closure plug 77, from whence it has communication to the slot 73 in the front of the nozzle plug thru an axial passageway 75. A needle valve 59' controls the passageway 75, this needle valve having threaded engagement in the outer end of the plug 77 and having a cap or handle 61 secured to its outer end by which the needle valve may be adjusted. A spring ball 62 is 90 adapted to bear against the inside of the flange on the cap 61 so as to retain the valve in any adjusted position. A small packing nut 63 is threaded into the open end of the plug 77 and holds a suitable packing 64 about 95 the stem of the needle valve 59'. 100
- 105 As described in the previous embodiment, the nozzle plug 72 can be adjusted, as by rotating the same, or the plug may be substituted by plugs having different sized or different shaped apertures for adjusting the low idling mixture. The reduced cylindrical portion 74 of the nozzle plug 72 may be milled around its circumference so that when the plug is forced into the hole, the 110 milled surface will grip the bore of the hole and resist accidental turning or loosening. Obviously, for adjusting, the plug may be backed out of the hole and then reinserted at a different angle. 115
- 120 In Figures 2 and 3, the nozzle plug 72 has the discharge opening 73 disposed eccentrically in the face of the plug. The slot 73 is formed in the reduced portion 74 of the plug and receives fuel thru a hole 75 125

extending diagonally thru the enlarged portion of the plug. As shown in Figure 2, the fuel passageway 24' opens into the annular area 70 surrounding the end of the closure plug 77. Radial holes 55' conduct the fuel into the bore of the closure plug from whence it enters the diagonal passage 75 under the control of the valve 59'. By this arrangement the slot 73 remains in communication with the fuel tube 24' even though the plug 72 is adjusted thru a wide range of angular movement. Where no air is admitted through the closure plug, a suitable air port 60 is provided to discharge into the passageway 24' below the idling nozzle.

By virtue of the eccentric disposal of the slot 73, it will be noted that different proportions of effective slot opening may be disposed either above or below any given position of the throttle by the mere rotation of the plug. For example, with a given throttle position such as shown in Figure 3, it will be observed that by rotating the plug counter-clockwise, that portion of the slot area above the lip of the throttle may be increased, or the entire slot area may be disposed above the lip of the throttle; and conversely, by rotating the plug in a clockwise direction, the greater proportion or the entire area of the slot opening may be disposed below the lip of the throttle. This also enables the nozzle opening to be quickly and easily adjusted to take care of the slight variations in the location of the throttle lip in position of closed throttle. As we have previously remarked, it would require painstaking and expensive machining to insure that the throttle lip of every carburetor of the same design would stop at precisely the same point in the carburetor barrel. The adjustability of the present nozzle plug dispenses with the necessity for accurate construction or assembly of the parts, as its wide adjustment is ample to take care of all variations resulting from mechanical discrepancies.

The proportions of the various idling mixtures can be very conveniently adjusted by the rotation of this nozzle plug. A higher suction always prevails on the upper side of the throttle during idling than on the lower side, and by rotating a greater or lesser area of the slot opening into communication with the higher suction zone above the throttle, or the lower suction zone below the throttle, practically any desired rate of fuel feed can be obtained. When the throttle is intersecting the idling nozzle port there is probably an impingement action, either of the fuel particles striking the lip of the throttle or the high velocity air impinging against the bottom of the port and the fuel issuing therefrom. It will be apparent that any of the present adjustments

of the fuel port may be made to modify this impingement action.

In Figures 4 and 5 we have shown a modified construction employing an eccentrically disposed port 78 of generally circular form 70 in combination with a slot 79 leading therefrom. Fuel enters the circular port 78 thru a transverse bore 81, arranged to communicate with the tube 24. In the adjustment of this type of plug, the circular port may be disposed below the lip of the throttle and the slot above, or vice versa, or the areas of both the port and the slot may be distributed partly above and partly below the lip of the throttle. This slot may perform a deflecting or directing function for the mixture in the port 78.

In Figures 6 and 7 a portion of the plug is milled off or cut away transversely as indicated at 82. That portion of the plug opening 32 which is thus left void by milling off the plug, constitutes the idling nozzle. It will be apparent that by rotating the plug this nozzle portion of the plug opening 32 may be shifted to practically any point 90 around the circumference of the hole so that the nozzle opening may be disposed above, below or across the throttle lip in any desired ratio. One such position is indicated in dotted lines.

In Figures 8 and 9 this plug is formed with a port 84 of a generally circular form which is disposed eccentric to the plug. Rotation of the plug will dispose this port either above, or below, or straddling the lip of the 100 throttle, (the latter as shown in dotted lines) in the same manner described in the previous embodiments.

Another modification of the invention is disclosed and claimed in applicants' copending application Serial No. 438,278, filed March 24, 1930, which is a continuation in part of this application.

The numerous modifications illustrated are only indicative of the large number of methods of carrying the invention into effect. They are all different manifestations of the one generic invention. The appended claims have been drawn to the end of covering these various methods of effecting the 115 one common invention, and such others as would naturally occur to one skilled in the art.

We claim:

1. In a carburetor, the combination of a carbureting chamber having a throttle valve therein, the wall of said chamber having a plug chamber therein, a nozzle plug at the inner end of said plug chamber having a fuel port terminating in said carbureting chamber adjacent to the edge of the throttle valve when the valve is closed, said nozzle plug being rotatable whereby its fuel port may be adjusted relative to the throttle valve, a separate plug threading into the outer end of 130

- 6 said plug chamber to abut against said nozzle plug to lock said nozzle plug in adjusted position, said nozzle plug having a passage leading to said fuel port, and a valve carried by said separate plug for cooperating with the outer end of said passage. 70
- 10 2. In a carburetor, a carbureting chamber having a throttle valve therein, a side wall of said chamber having a bore therethrough, the valve having a lip adapted in substantially closed position to overhang the said bore, a rotatable idling plug disposed in said bore and having an idling passageway formed therein, there being a passageway for supplying liquid fuel to said idling passageway, said idling passageway being eccentric relative to the axis of said plug for adjustment of the position of the same under the lip of the throttle to vary the quality of the mixture of fuel and air supplied by the carburetor by rotation of said plug. 75
- 15 3. In a carburetor, the combination of a mixture passageway, a throttle controlling the same, and a fuel port for discharging fuel and air adjacent the lip of said throttle when the latter is in a restricted position, the position of said fuel port being adjustable relative to said throttle. 80
- 20 4. In a carburetor, the combination of a carbureting passageway, a throttle controlling flow through said passageway and a fuel port for discharging fuel and air into said passageway adjacent said throttle, said port being adjustable longitudinally of said passageway. 85
- 25 5. In a carburetor, the combination of a carbureting passageway, a throttle controlling the same, a fuel plug having a port discharging fuel and air into said passageway adjacent said throttle, said fuel plug being rotatable for shifting the location of said port relative to said throttle. 90
- 30 6. In a carburetor, the combination of a carbureting passageway, a throttle controlling the same, a nozzle having a nozzle plug discharging fuel into said passageway adjacent said throttle, said plug being rotatable for shifting said nozzle longitudinally of said passageway. 95
- 35 7. In a carburetor, the combination of a carbureting chamber, a throttle in said chamber, a fuel passageway arranged to discharge fuel into the carbureting chamber adjacent the edge of said throttle when the latter is in a restricted position and means for shifting the point of discharge of said fuel passageway relative to said throttle. 100
- 40 8. In a carburetor, the combination of a body portion having a carbureting passageway extending therethrough, a plug separate from said body portion and disposed in an opening therein, said plug having a fuel port discharging fuel into said passageway and being rotatable to adjust the location of said port. 105
- 45 9. In a carburetor, the combination of a carbureting chamber having a throttle therein, the wall of said chamber having an aperture therein adjacent said throttle, an idling nozzle plug in said aperture and having a fuel port for discharging fuel and air into said carbureting chamber, said nozzle plug being removable for substitution or adjustment, and a co-operating closure plug behind said nozzle plug. 110
- 50 10. In a carburetor, the combination of a carbureting chamber having a throttle therein, the wall of said chamber having an aperture therethrough adjacent said throttle, a fuel nozzle plug in said aperture having a port for discharging fuel into said carbureting chamber, said nozzle plug being rotatable for adjusting the location of said port relative to said throttle and a cooperating closure plug engaging in said aperture in back of said nozzle plug. 115
- 55 11. In a carburetor, the combination of a carbureting chamber, a fuel nozzle plug removably and rotatably mounted to discharge into said carbureting chamber, said plug having a fuel port discharging fuel into said chamber and disposed eccentrically therein, the rotatable adjustment of said plug operating to shift the location of said port. 120
- 60 12. In a carburetor, the combination of a carbureting chamber having a throttle therein, the wall of said chamber having an aperture extending therethrough adjacent said throttle, a nozzle plug seated in said aperture, said plug having a fuel discharging slot extending transversely thereof, and a co-operating closure plug in back of said nozzle plug. 125
- 65 13. In a carburetor, the combination of a carbureting chamber having a throttle therein, the wall of said chamber having an aperture therein adjacent said throttle, an idling nozzle plug seated in said aperture, a fuel supply passageway extending through the wall of said carbureting chamber and communicating with said plug, said plug having one side thereof cut off to provide a fuel port discharging from one side of said plug, said fuel port being shiftable relative to the edge of said throttle by the rotation of said plug. 130
- 70 14. In a carburetor, the combination of a cylindrical carbureting passageway having a throttle valve therein, the wall of said passageway having a plug chamber extending radially, an idling fuel nozzle plug at the inner end of said chamber having an eccentric port terminating in said carbureting chamber adjacent to the edge of said throttle valve when the valve is closed, said nozzle plug being rotatable without longitudinal movement for adjusting the fuel port relative to the throttle valve. 135
- 75 15. In a carburetor having a carbureting chamber, an idling device comprising a radial

- bore in the wall of said chamber adapted to accommodate one of a plurality of idling nozzle plugs having different sized fuel orifices for metering and regulating the low idling mixture, means for supplying air and liquid fuel to said plug, and means for shifting the position of said plug in said chamber for regulating the high idling mixture.
16. In a carburetor having a carbureting chamber, a main jet nozzle and a throttle valve in said chamber, an idle fuel feed from the interior of the main jet nozzle into said chamber through a metering orifice and openings above and below the edge of said throttle when same is closed, means for adjusting the size of said openings relative to each other, and means for adjusting the fuel feed through said metering orifice including an adjustable air vent.
17. In a carburetor, a carbureting chamber having a throttle valve therein, a radial opening in the side wall of said chamber so located as to be overhung by the lip of said throttle when same is in restricted position, a movable idling plug disposed in said opening and having an idling fuel passageway therein, there being a duct for supplying liquid fuel to said idling passageway, said idling passageway being movable along the side wall of said chamber for adjustment relative to the lip of said throttle to vary the quality of idling mixture supplied by the carburetor.

In witness whereof, we hereunto subscribe our names this 20th day of April, A. D. 1922.

FRANK C. MOCK.
